CYLINDER GRINDER

John M. Krohn, Racine, and Eugene H. Simpson,
West Allis, Wis.

Application November 22, 1934, Serial No. 754,210

21 Claims. (Cl. 51—34)

This invention relates to cylinder grinding or honing machines particularly adapted to grind or finish engine cylinders.

In the grinder art considerable difficulty has been encountered in grinders in which a plurality of stones are mounted on a single block because the stones drift and cause the resulting hole to vary from the true perpendicular by considerable amounts. This is particularly true in portable machines in which the construction is relatively light and the mounting insecure.

One object of the invention therefore is to provide a cylinder grinding machine of the type which will grind the cylinder with the axis thereof truly perpendicular to the axis of the crank shaft.

Another object of the invention is to provide a portable grinding machine which is light and efficient and which will rebore a hole truly perpendicular to the crank shaft under all conditions.

A further object of the invention is to provide a grinding element with an increased range of expansion having an improved mechanism to effect positive and uniform radial expansion of the grinding diameter.

In most of the grinders now on the market the stones are mounted on conical expanders which provide for a limited expansion only. These expanders have the obvious disadvantage of allowing one end of the stone to grind at a greater radius than the other end, causing variation in the diameter of the hole.

It is another object of the present invention to provide a grinder mounting which will maintain the stones at a given diameter throughout the length thereof and which will increase the range of diameters through which the grinder will operate.

Another object of the invention is to provide an improved mechanism for automatically expanding the diameter of the stones at the beginning of the longitudinal strokes of the stones.

Other objects of the invention are to increase the flexibility and range of adaptability of cylinder grinding and honing machines, to produce a machine which will be relatively simple to manufacture and use, and which will reduce the initial cost of grinding and the cost of reborning.

Other objects will be apparent from the following description.

Two embodiments of the invention are disclosed in the accompanying drawings and will be described in the following specification.

In the drawings:

Fig. 1 is an elevational view partly in cross-

section of a cylinder grinding or honing machine as applied in the manufacture of engines, with a cylinder block in place.

Fig. 2 is a side view of the machine shown in Fig. 1 with the cylinder block removed. 5

Fig. 3 shows a cross-section of the lower portion of the automatic stone expanding mechanism of the machine as shown in Figs. 1 and 2.

Fig. 4 is a cross-section of the upper portion of the automatic stone expanding mechanism 10 shown in Figs. 1 and 2, and is a continuation of Fig. 3.

Figs. 5 and 6 are cross-sections on the lines 5—5 and 6—6 of Fig. 3 looking in the direction of the arrows. 15

Figs. 7 and 8 are cross-sections on the lines 7—7 and 8—8 respectively of Fig. 6 looking in the direction of the arrows.

Fig. 9 is a cross-section on the line 9—9 of Fig. 4 looking in the direction of the arrows. 20

Figs. 10 and 11 are cross-sections on the lines 10—10 and 11—11 respectively, of Fig. 3, looking in the direction of the arrows.

Fig. 12 is a vertical cross-section of a manual expander used on portable grinding machines. 25

Fig. 13 is a cross-section on the line 13—13 of Fig. 12 looking in the direction of the arrows.

Fig. 14 is a vertical cross-section through the lower support in a portable grinding or honing machine of the type shown in Fig. 12. 30

Fig. 15 is a cross-section on the line 15—15 of Fig. 14 looking in the direction of the arrows.

In the drawings in which like numerals indicate like parts throughout the several views two embodiments of the invention are disclosed. 35 Figs. 1 to 11 inclusive show a factory or production type cylinder grinder for use in the manufacture of engines or the like, in which a relatively heavy fully automatic machine is required, while Figs. 12 to 15 inclusive show a portable type machine designed primarily for reborning or honing work in garages. 40

Referring to Figs. 1 and 2 which show complete assemblies of a production type machine in two planes, the grinder is shown mounted on a standard 28, which extends over a grinding table 21. The table 21 holds a cylinder block 22 comprising one or more cylinders to be ground and honed to size by a grinder or hone 23. 45

The standard 28 has a bracket 24 formed on one side thereof which supports a motor 25 or other prime mover. The motor 25 operates a pair of bevel gears 26—26 through a pulley and belt 27. The bevel gears 26 turn a driving gear 28 with a set of shiftable gears 29 and 30 inter- 50

posed between the gears 26 and the gear 28 to provide a plurality of desirable speeds. The changes in gear ratio are effected through a pair of shift levers 31 and 32 in the usual manner.

5 The driving gear 28 turns a gear 33 which is splined on a hollow spline shaft 34 which rotates the hone 23. The spline shaft 34 runs in bearings 35 and 36, with interitorly splined sleeves 37 and 38 interposed therebetween. This permits 10 free rotation of the spline shaft 34 as well as free axial movement.

The spline shaft 34 is connected with the grinder or hone 23, by a flanged coupling 39 so that rotation of the spline shaft rotates the 15 stones and reciprocation of the spline shaft causes a corresponding reciprocation of the stones.

The hone 23 is reciprocated by means of a hydraulic motor comprising a double acting cylinder 40 containing a piston 41 which drives a piston 20 rod 42. Fluid, such as oil, is supplied from a pump 43 through feed pipes 44 and 45 to the upper and lower ends respectively of the cylinder 40 to reciprocate the piston 41. A valve 46 directs fluid from the pump 43 alternately to the upper and 25 lower sides of the piston 41. While fluid is being delivered to one side of the piston 41 it is being withdrawn from the other side of the piston through the valve 46 and returned to the pump 43.

The valve 46 is operated by a finger 47 which 30 actuates a double arm valve trip 48 at the opposite ends of the piston stroke to reverse the flow of fluid in the pipes 44 and 45.

As shown in Figs. 1, 3 and 4 the piston rod 42 terminates in a cup like plug 49 fitting in the interior of the hollow spline shaft 34. The plug 49 has a thrust bearing 50 which permits the transmission of longitudinal stress to the hone 23 while permitting free rotation of the hone relative to the piston rod 42.

40 The plug 49 is connected to a driving sleeve 51 which is suitably keyed to the interior of the spline shaft 34 so as to permit limited axial movement of the sleeve relative to the spline shaft. Axial movement is transmitted from the sleeve 51 to the spline shaft 34 through a shoulder 52 formed on the interior of the spline shaft on the lower end, and through a split ring stop 53, or its equivalent, adjacent the upper end of the spline shaft.

50 Provision is made for a small amount of lost motion between the driving sleeve 51 and the spline shaft 34. This lost motion occurs at the beginning of both the up and down strokes of the piston, and is utilized to expand the stones of the 55 grinder or hone 23, in a manner described below.

Referring particularly to Figs. 5 to 8 inclusive, the grinder or hone 23 is composed of a plurality of stones 54 which are mounted on holders 55 supported by rods 56 which have gear teeth 57 cut 60 in one side thereof. Each stone is supported by two or more such rods to assure a rigid mounting in a mounting block 58, which contains gears 59 and 60 at the top and bottom respectively of the grinder which mesh with the teeth 57 in the rods 65 56 to alter or maintain the grinding radius. The gears 59 and 60 are of equal diameter and both keyed on shafts 61 which insures a uniform radial movement of both ends of the stones.

The gears 59 are provided with two sets of teeth, 70 one of which meshes with the teeth 57 in the rods 56, and a second set, in a single plane, which engage with the teeth of a master gear 62 positioned on the upper part of the block 58 and located concentrically with the stones 54. Certain of the 75 gears 59 and 60 have blank portions to permit the

passage of rods 56 therewith. Rotation of the gear 62 turns all the gears 59, which in turn rotate the gears 60 through the shafts 61 to expand the stones 54.

The gear 62 is keyed to an actuating shaft 63 which extends through the flanged coupling 39 and into the driving sleeve 51, where it is suitably supported in bearings 64-64. Manual rotation of the actuating shaft 63 is effected through a worm and worm wheel 65 to set the stones to an 10 initial diameter, from which point they are automatically expanded by the action of the driving sleeve 51 in the following manner.

The actuating shaft 63, Figs. 3 and 4, has a pair of cam slots 66 which are engaged by cam pins 67 fixed in actuating cones 68 and 69 which are mounted for limited axial movement on the shaft 63 and rotate therewith. The actuating cones carry overriding clutches 70 which are engaged by driving cones 71 and 72, which impart an axial 20 movement to the actuating cones while the clutches prevent relative rotation between the driving and the actuating cones during driving.

One type of overriding clutch is shown in which the balls ride in a race having a ratchet section 25 70a cut in the inner face of the race so that the clutch drives in one direction only. While this clutch is thought desirable other types of clutches may also prove satisfactory.

The axial movement of the actuating cones 68 30 and 69 causes the pins 67 to move in the cam slots 66 and turn the actuating shaft, which expands the stones. By using two cam slots 66, as shown in Figs. 3 and 4, expansion can be made to occur at the beginning of both the up and the down 35 strokes of the stones.

The driving cones are keyed to rotate with the spline shaft 34, and are moved longitudinally in one direction by the driving sleeve 51 and returned by springs 73 which act against collars 74 40 fixed to the shaft 63.

The actuating cones 68 and 69 are constantly urged toward the driving cones 71 and 72 respectively, by springs 75 and 76. The springs 75 and 76 supply the necessary pressure between the 45 driving and the actuating cones to cause the friction clutch 70 to drive.

Keys 77 and 78 are provided in the driving cones 71 and 72 to permit limited lateral movement of the driving cones relative to the spline 50 shaft 34 while preventing relative rotation between the two.

The actuating cones 68 and 69 are positively disengaged from the driving cones 71 and 72 respectively, by wedge keys 79 interposed between 55 the actuating cones 68 and 69 and the actuating shaft 63. The wedge key has a pair of spaced fingers 80 and 81. The finger 80 has a spring 82 interposed between it and the small end of the actuating cone and a second, stronger spring 83 60 between it and an interior annular flange 84 on the driving cone.

When the driving cone 71 or 72 moves into contact with the actuating cone 68 or 69 the annular flange 84 presses the wedge into engagement 65 between the shaft 63 and the actuating cone so as to permit longitudinal movement of the cone in one direction only. When the driving cone 71 or 72 retracts, the actuating cone 68 or 69 is held against following until the annular flange 84 70 strikes the finger 81. Contact of the flange 84 with the finger 81 breaks the connection between the cone 68 or 69 and the shaft 63 and enables the cone 68 or 69 to move back to its original position under the influence of the springs 75 and 75

76. The spring 82 holds the wedge out of engagement with the keyway and permits the actuating cones 68 and 69 to return to normal position as soon as the wedge is released.

5 Referring to Fig. 1, it will be seen that the lower end of the grinder or hone 23 is provided with a guide cylinder 85 which fits over a piston or guide rod 86. The rod 86 passes through the grinding table 21 and into a cylinder 81, where 10 a piston is attached to it for operation in the cylinder. The upper and lower parts of the cylinder 81 are connected to the pump 43 and the pump is made operable after a predetermined number of strokes to withdraw the piston or guide 15 rod from the guide cylinder 85.

The guide cylinder and rod form a support for the lower end of the grinder and insure a truly perpendicular hole being ground in the cylinder block.

20 Since garages and repair shops cannot put in equipment of this character, a light hone has been developed using the principles disclosed above, except that it does not automatically expand the stones. This grinder is shown in Figs. 25 12 to 15 inclusive.

Fig. 14 shows the lower portion of the grinding or honing machine for use in garages. The grinding or honing machine has a set of stones 88 mounted on a block 89. The block 89 is formed 30 with stub shafts 90 and 91 on the top and bottom thereof respectively.

35 The lower stub shaft 91 operates in a cylinder 92, which is fastened to the crank shaft 93 of the engine. The cylinder 92 forms a guide for the lower end of the grinder, and prevents drift of the stones.

A yieldable support, generally designated 94 aids in maintaining the guide rod or stub shaft 91 truly axial in the hole. The details of the support 94 are shown in Figs. 14 and 15. The support 94 has a cylinder 95 which has a working fit on the exterior of the guide cylinder 92. The cylinder 95 is constantly urged upward by a spring 96, and limited in its upward movement 45 by a retaining sleeve 97, adjustably fixed to the lower end of the guide cylinder 92.

50 Yieldable fingers 98 are mounted for limited radial movement on the top of the cylinder 25, and are pressed outwardly by springs 99 into engagement with the walls of the engine cylinder. A guide block 100 supports guide pins 101 which limit the radial movement of the fingers 98 and form guides for springs 99.

55 The lower support or guide 94 is fixed on the crank shaft 93 by means of a saddle 102 which is clamped on the crank shaft and attached to the lower end of the guide cylinder 92.

In operation the grinder 88 reciprocates with a 60 stroke slightly greater than the length of the cylinder. When the grinder block 89 comes in contact with the yieldable support 94 it shoves the cylinder 95 down against the action of the spring 96, and forces the guide block 100 and the fingers 98 out of the cylinder and permits the 65 grinder 88 to hone the lower edge of the cylinder. When the grinder 88 goes upward in the cylinder, the fingers 98 again enter the cylinder and form an additional support for the stub shaft 91.

65 Referring to Fig. 12, the upper end of the 70 grinder 88 is supported over the cylinder to be ground by a frame (not shown) which clamps on the upper surface of the cylinder block.

75 Power is transmitted from an electric motor or other suitable power source to a shaft 103 which is fastened to the stub shaft 90 by a suit-

able connection. The stub shaft 90 is formed integrally with the block 89 and rotates the grinder.

The stones are expanded through a graduated collar 104 which turns freely on the stub shaft 90 and is attached to a bevel gear 105 which is 5 mounted to turn on the stub shaft 90. The gear 105 is enclosed in a housing 106, where it meshes with a bevel gear 107 on the side of the housing 106. The bevel gear 107 drives a bevel gear 108, as shown in Fig. 13, which is keyed on 10 a shaft containing a worm 109.

The worm 109 turns a worm wheel 110 which is mounted on the stub shaft 90. The worm wheel 110 is made integral with a master gear 111, comparable to the master gear 82 described 15 above. The master gear 111 operates gears 88 to expand the stones as described above, and as shown on Figs. 5 to 8 inclusive.

Operation

20

The hone shown in Figs. 1 to 11 inclusive is permanently mounted on the frame 20 and in order to grind or hone a cylinder, the cylinder 22 is placed on the table and the piston rod 86 brought up by suitable operation of the piston 25 attached thereto. The hone 23 is then lowered with the stones retracted until the piston rod 30 86 engages with the cylinder 85.

The hone is then moved to either the upper or lower end of the stroke, at which point both 35 the clutches 70 are disengaged. A key is inserted (Fig. 11) on a square end of the shaft carrying the worm 65 to expand the stones to the initial grinding diameter.

A counter (not shown) is set to completely 35 withdraw the stones from the cylinder at the end of the predetermined number of strokes necessary to reach the required diameter.

The stones are then started rotating through the gears 26, 29, 30, 28 and 33. At the same time 40 fluid is delivered to the cylinder 40 to reciprocate the stones in the cylinder 22.

At the beginning of the down stroke of the hone 23 the sleeve 51 moves the driving cone 12 into engagement with the clutch 70 in the actuating cone 68 and at the same time, the annular collar 84 engages the spring 83 and forces the wedge key 80 into engagement between the cone 68 and the actuating shaft 63. Further movement of the driving cone 12 causes the actuating cone to move down with the cam pin 67 engaging the cam slot 66 to turn the shaft 63 and expand the stones a set amount.

When the hone 23 starts up, the driving cone 12 is moved up by the spring 73 and disengages 55 from the clutch 70 in the actuating cone. The actuating cone 70 is prevented from following by the wedge key 80, which holds the cone 68 in its lowermost position until the key 80 is disengaged by upward pressure of the ring 84 on the finger 81.

When the ring 84 engages the finger 81 to disengage the key 80 the spring 82 acts to maintain the key 80 disengaged while the spring 76 moves the cone 68 back to its original position.

It will be noted that the cone 68 is free to rotate 65 on the shaft when disengaged from the driving cone 12, and hence the cam pin 67 returns to its original position without turning the shaft 63.

On the upstroke, a similar action takes place 70 between the driving cone 71 and the actuating cone 68.

When a predetermined number of strokes are completed, a counter (not shown) operates to withdraw the hone 23 from the cylinder 22 and at the same time the piston rod 86 is withdrawn 75

through the movable portion of the table 21 to permit removal of the cylinder block.

In operation, the portable hone shown in Figs. 12 to 15 inclusive is set on top of a cylinder block with a supporting frame (not shown) fixed to the top of the block over a cylinder to guide the grinder or hone 23 axially into the cylinder.

The saddle 102 is fixed to the crank shaft 93 with the latter at dead center. The fingers 98 are adjusted in the lower end of the cylinder 22 and the stub shaft 91 guided into the cylinder 92.

The grinder 23 may then be rotated by a motor (not shown) and at the same time the hone is reciprocated manually.

Expansion of the stones 88 is effected by stopping the motor and turning the graduated collar as explained above.

When the grinder 23 reaches the lower part of the cylinder 22, the block 100 is pushed down by the lower edge of the grinder, which moves the fingers out of the cylinder and permits the lower part of the cylinder to be ground to the same diameter as the remainder of the cylinder.

When the grinder 23 moves up in the cylinder 25 the spring 96 forces the fingers 98 up and into the cylinder to form an intermediate support between the upper and lower supports.

If desired the grinder shown in Figs. 12 to 15 inclusive may be reciprocated by a hydraulic drive similar to that shown in Figs. 1 and 2.

Having thus described the invention, it is realized that it is susceptible to various changes and modifications without resorting to invention. It is not, therefore, desired to limit the invention to the particular forms herein shown and described, but only by the scope of the appended claims.

What is claimed as new and desired to secure by Letters Patent is:

1. A cylinder grinding machine of the character described comprising, a grinder mounting block adapted for axial reciprocation in a cylinder to be ground, and rotatable on the axis of the cylinder, a plurality of stones mounted axially on said block and adapted to expand radially thereto, means in said block to expand said stones radially, a hollow spline shaft having a driving connection with the block to rotate the same, means to reciprocate said block, an actuating shaft mounted in the spline shaft and having an operating connection with the stone expanding means to effect operation thereof, and means in said spline shaft, engageable with said second named shaft to effect rotation of the second named shaft relative to the spline shaft at a predetermined point in the axial movement of the grinder.

2. A cylinder grinding machine as defined in claim 1 including manual means to effect rotation of the actuating shaft relative to the spline shaft at predetermined points in the stroke.

3. A cylinder grinding machine as defined in claim 1 in which the last named means includes a cam groove in the actuating shaft and a cam follower driven by the means to reciprocate the block.

4. A cylinder grinding machine as defined in claim 1 in which said last named means includes a releasable clutch.

5. A cylinder grinding machine adapted to grind the cylinders of an engine having a crank shaft, and comprising a grinder body having a supporting shaft on the lower side thereof, a plurality of stones mounted on said body to move axially therewith in the engine cylinder and expand radially thereto, means to reciprocate and ro-

tate said stones within the cylinder, and means clamped on the crank shaft and engaging the supporting shaft to insure against drift in grinding.

6. A cylinder grinding machine adapted to 5 grind the cylinders of an engine having a crank shaft, and comprising a grinder body, a supporting shaft on the lower side of said body, a plurality of stones mounted on said body to move axially therewith in the engine cylinder and expand 10 radially thereto, means to reciprocate and rotate said stones within the cylinder, and means clamped on the crank shaft and yieldably engaging the sides of said cylinder to engage the said supporting shaft and guide the lower end 15 of the grinder to prevent drift.

7. A cylinder grinding machine of the character described comprising, a plurality of stones mounted to reciprocate axially in a cylinder to be ground and expand radially therein, means to support the stones over an engine with the stones alined with the cylinder to be ground, means including a clamp attached to the crank shaft of the engine when the said shaft is at dead center and a guide cylinder and guide rod operable 25 therein to maintain the lower end of the stones in alinement in the cylinder.

8. A cylinder grinding machine of the character described comprising, a plurality of stones mounted to move axially within a cylinder to be 30 ground and expand radially therein, means to rotate and reciprocate said stones within the cylinder to grind the same, means on one end of said cylinder to maintain said stones alined in said cylinder, means on the other end of said cylinder 35 to maintain said stones in alinement, and means in one end of said cylinder to form a brace between said stones and said last named support while grinding.

9. A cylinder grinding machine of the character 40 described comprising, a plurality of stones mounted to move axially within a cylinder and expand radially therein, means on one end of said cylinder to maintain said stones alined in said cylinder, means on the other end of said cylinder to maintain said stones in alinement, and means in one end of said cylinder retractable therefrom by the action of the stones to form a brace between said stones and said last named support.

10. In a cylinder grinder of the character described, a mounting block adapted to rotate about a vertical axis, a first pair of parallel racks mounted in apertures in said block intersecting the axis thereof, a grinding stone carried by said racks parallel to said axis, a second pair of parallel racks mounted in apertures in said block intersecting said axis at different elevations from said first pair of racks, a grinding stone carried by said second pair of racks parallel to said axis, a first pair of gears mounted to rotate together on a common axis and engaging the teeth of the first pair of racks to move the stone radially while maintaining the stone parallel to said axis, a second pair of gears mounted to rotate together on a common axis and engaging the teeth of said second pair of racks to move the stone carried thereby radially while maintaining the stone parallel to said axis, a master gear engaging one gear of each pair of gears to move both stones simultaneously, and means to rotate said master gear 70 to effect expansion of the stones.

11. In a machine tool having radially expandable cutting elements, a hollow shaft mounted for rotational and limited axial movement and connected to the said cutting elements to effect 75

76. The spring 82 holds the wedge out of engagement with the keyway and permits the actuating cones 88 and 89 to return to normal position as soon as the wedge is released.

5 Referring to Fig. 1, it will be seen that the lower end of the grinder or hone 23 is provided with a guide cylinder 85 which fits over a piston or guide rod 86. The rod 86 passes through the grinding table 21 and into a cylinder 81, where 10 a piston is attached to it for operation in the cylinder. The upper and lower parts of the cylinder 81 are connected to the pump 48 and the pump is made operable after a predetermined number of strokes to withdraw the piston or guide 15 rod from the guide cylinder 85.

The guide cylinder and rod form a support for the lower end of the grinder and insure a truly perpendicular hole being ground in the cylinder block.

20 Since garages and repair shops cannot put in equipment of this character, a light hone has been developed using the principles disclosed above, except that it does not automatically expand the stones. This grinder is shown in Figs. 12 to 15 inclusive.

Fig. 14 shows the lower portion of the grinding or honing machine for use in garages. The grinding or honing machine has a set of stones 88 mounted on a block 89. The block 89 is formed 30 with stub shafts 90 and 91 on the top and bottom thereof respectively.

35 The lower stub shaft 91 operates in a cylinder 92, which is fastened to the crank shaft 88 of the engine. The cylinder 92 forms a guide for the lower end of the grinder, and prevents drift of the stones.

40 A yieldable support, generally designated 94 aids in maintaining the guide rod or stub shaft 91 truly axial in the hole. The details of the support 94 are shown in Figs. 14 and 15. The support 94 has a cylinder 95 which has a working fit on the exterior of the guide cylinder 92. The cylinder 95 is constantly urged upward by a spring 96, and limited in its upward movement 45 by a retaining sleeve 97, adjustably fixed to the lower end of the guide cylinder 92.

50 Yieldable fingers 98 are mounted for limited radial movement on the top of the cylinder 23, and are pressed outwardly by springs 99 into engagement with the walls of the engine cylinder. A guide block 100 supports guide pins 101 which limit the radial movement of the fingers 98 and form guides for springs 99.

55 The lower support or guide 94 is fixed on the crank shaft 88 by means of a saddle 102 which is clamped on the crank shaft and attached to the lower end of the guide cylinder 92.

60 In operation the grinder 88 reciprocates with a stroke slightly greater than the length of the cylinder. When the grinder block 88 comes in contact with the yieldable support 94 it shoves the cylinder 95 down against the action of the spring 96, and forces the guide block 100 and the fingers 98 out of the cylinder and permits the 65 grinder 88 to hone the lower edge of the cylinder. When the grinder 88 goes upward in the cylinder, the fingers 98 again enter the cylinder and form an additional support for the stub shaft 81.

65 Referring to Fig. 12, the upper end of the 70 grinder 88 is supported over the cylinder to be ground by a frame (not shown) which clamps on the upper surface of the cylinder block.

75 Power is transmitted from an electric motor or other suitable power source to a shaft 103 which is fastened to the stub shaft 88 by a suit-

able connection. The stub shaft 88 is formed integrally with the block 89 and rotates the grinder.

The stones are expanded through a graduated collar 104 which turns freely on the stub shaft 88 and is attached to a bevel gear 105 which is 5 mounted to turn on the stub shaft 88. The gear 105 is enclosed in a housing 106, where it meshes with a bevel gear 107 on the side of the housing 106. The bevel gear 107 drives a bevel gear 108, as shown in Fig. 13, which is keyed on 10 a shaft containing a worm 109.

The worm 109 turns a worm wheel 110 which is mounted on the stub shaft 88. The worm wheel 110 is made integral with a master gear 111, comparable to the master gear 82 described 15 above. The master gear 111 operates gears 88 to expand the stones as described above, and as shown on Figs. 5 to 8 inclusive.

Operation

20

The hone shown in Figs. 1 to 11 inclusive is permanently mounted on the frame 20 and in order to grind or hone a cylinder, the cylinder 22 is placed on the table and the piston rod 86 brought up by suitable operation of the piston attached thereto. The hone 23 is then lowered with the stones retracted until the piston rod 86 engages with the cylinder 85.

The hone is then moved to either the upper or lower end of the stroke, at which point both 30 the clutches 70 are disengaged. A key is inserted (Fig. 11) on a square end of the shaft carrying the worm 65 to expand the stones to the initial grinding diameter.

A counter (not shown) is set to completely 35 withdraw the stones from the cylinder at the end of the predetermined number of strokes necessary to reach the required diameter.

The stones are then started rotating through the gears 26, 29, 30, 28 and 33. At the same time 40 fluid is delivered to the cylinder 40 to reciprocate the stones in the cylinder 22.

At the beginning of the down stroke of the hone 23 the sleeve 51 moves the driving cone 72 into engagement with the clutch 70 in the actuating 45 cone 69 and at the same time, the annular collar 84 engages the spring 83 and forces the wedge key 80 into engagement between the cone 69 and the actuating shaft 63. Further movement of the driving cone 72 causes the actuating cone 50 to move down with the cam pin 67 engaging the cam slot 66 to turn the shaft 63 and expand the stones a set amount.

When the hone 23 starts up, the driving cone 72 is moved up by the spring 73 and disengages 55 from the clutch 70 in the actuating cone. The actuating cone 70 is prevented from following by the wedge key 80, which holds the cone 69 in its lowermost position until the key 80 is disengaged by upward pressure of the ring 84 on the finger 81.

When the ring 84 engages the finger 81 to disengage the key 80 the spring 82 acts to maintain the key 80 disengaged while the spring 76 moves the cone 69 back to its original position.

It will be noted that the cone 69 is free to rotate 65 on the shaft when disengaged from the driving cone 72, and hence the cam pin 67 returns to its original position without turning the shaft 63.

On the upstroke, a similar action takes place between the driving cone 71 and the actuating 70 cone 68.

When a predetermined number of strokes are completed, a counter (not shown) operates to withdraw the hone 23 from the cylinder 22 and at the same time the piston rod 86 is withdrawn 75

through the movable portion of the table 21 to permit removal of the cylinder block.

In operation, the portable hone shown in Figs. 12 to 15 inclusive is set on top of a cylinder block with a supporting frame (not shown) fixed to the top of the block over a cylinder to guide the grinder or hone 23 axially into the cylinder.

The saddle 102 is fixed to the crank shaft 93 with the latter at dead center. The fingers 98 are adjusted in the lower end of the cylinder 22 and the stub shaft 91 guided into the cylinder 92.

The grinder 23 may then be rotated by a motor (not shown) and at the same time the hone is reciprocated manually.

15 Expansion of the stones 88 is effected by stopping the motor and turning the graduated collar as explained above.

When the grinder 23 reaches the lower part of the cylinder 22, the block 100 is pushed down by 20 the lower edge of the grinder, which moves the fingers out of the cylinder and permits the lower part of the cylinder to be ground to the same diameter as the remainder of the cylinder.

When the grinder 23 moves up in the cylinder 25 the spring 96 forces the fingers 98 up and into the cylinder to form an intermediate support between the upper and lower supports.

If desired the grinder shown in Figs. 12 to 15 inclusive may be reciprocated by a hydraulic 30 drive similar to that shown in Figs. 1 and 2.

Having thus described the invention, it is realized that it is susceptible to various changes and modifications without resorting to invention. It is not, therefore, desired to limit the invention 35 to the particular forms herein shown and described, but only by the scope of the appended claims.

What is claimed as new and desired to secure by Letters Patent is:

40 1. A cylinder grinding machine of the character described comprising, a grinder mounting block adapted for axial reciprocation in a cylinder to be ground, and rotatable on the axis of the cylinder, a plurality of stones mounted axially on said block and adapted to expand radially thereto, means in said block to expand said stones radially, a hollow spline shaft having a driving connection with the block to rotate the same, means to reciprocate said block, an actuating shaft 45 mounted in the spline shaft and having an operating connection with the stone expanding means to effect operation thereof, and means in said spline shaft, engageable with said second named shaft to effect rotation of the second named shaft relative to the spline shaft at a predetermined point in the axial movement of the grinder.

50 2. A cylinder grinding machine as defined in claim 1 including manual means to effect rotation of the actuating shaft relative to the spline shaft at predetermined points in the stroke.

55 3. A cylinder grinding machine as defined in claim 1 in which the last named means includes a cam groove in the actuating shaft and a cam follower driven by the means to reciprocate the block.

60 4. A cylinder grinding machine as defined in claim 1 in which said last named means includes a releasable clutch.

65 5. A cylinder grinding machine adapted to 70 grind the cylinders of an engine having a crank shaft, and comprising a grinder body having a supporting shaft on the lower side thereof, a plurality of stones mounted on said body to move axially therewith in the engine cylinder and expand radially thereto, means to reciprocate and ro-

tate said stones within the cylinder, and means clamped on the crank shaft and engaging the supporting shaft to insure against drift in grinding.

6. A cylinder grinding machine adapted to 5 grind the cylinders of an engine having a crank shaft, and comprising a grinder body, a supporting shaft on the lower side of said body, a plurality of stones mounted on said body to move axially therewith in the engine cylinder and expand 10 radially thereto, means to reciprocate and rotate said stones within the cylinder, and means clamped on the crank shaft and yieldably engaging the sides of said cylinder to engage the said supporting shaft and guide the lower end 15 of the grinder to prevent drift.

7. A cylinder grinding machine of the character described comprising, a plurality of stones mounted to reciprocate axially in a cylinder to be ground and expand radially therein, means to 20 support the stones over an engine with the stones aligned with the cylinder to be ground, means including a clamp attached to the crank shaft of the engine when the said shaft is at dead center and a guide cylinder and guide rod operable 25 therein to maintain the lower end of the stones in alignment in the cylinder.

8. A cylinder grinding machine of the character described comprising, a plurality of stones mounted to move axially within a cylinder to be 30 ground and expand radially therein, means to rotate and reciprocate said stones within the cylinder to grind the same, means on one end of said cylinder to maintain said stones aligned in said cylinder, means on the other end of said cylinder 35 to maintain said stones in alignment, and means in one end of said cylinder to form a brace between said stones and said last named support while grinding.

9. A cylinder grinding machine of the character described comprising, a plurality of stones mounted to move axially within a cylinder and expand radially therein, means on one end of said cylinder to maintain said stones aligned in said cylinder, means on the other end of said cylinder to 45 maintain said stones in alignment, and means in one end of said cylinder retractable therefrom by the action of the stones to form a brace between said stones and said last named support.

10. In a cylinder grinder of the character described, a mounting block adapted to rotate about a vertical axis, a first pair of parallel racks mounted in apertures in said block intersecting the axis thereof, a grinding stone carried by said racks parallel to said axis, a second pair of parallel racks mounted in apertures in said block intersecting said axis at different elevations from said first pair of racks, a grinding stone carried by said second pair of racks parallel to said axis, a first pair of gears mounted to rotate together on a common axis and engaging the teeth of the first pair of racks to move the stone radially while maintaining the stone parallel to said axis, a second pair of gears mounted to rotate together on a common axis and engaging the teeth of said second pair of racks to move the stone carried thereby radially while maintaining the stone parallel to said axis, a master gear engaging one gear of each pair of gears to move both stones simultaneously, and means to rotate said master gear 60 to effect expansion of the stones.

11. In a machine tool having radially expandable cutting elements, a hollow shaft mounted for rotational and limited axial movement and connected to the said cutting elements to effect 75

- rotation thereof, means to expand said cutting elements radially, and means within said hollow shaft operable upon axial movement of said hollow shaft at a predetermined point in its stroke 5 to operate the cutter expansion means.
12. In a cylinder grinder adapted to grind the cylinder of an engine having a crank shaft, a grinder element adapted to reciprocate in the cylinder, a support for the upper end of said 10 grinder element above said cylinder, and a clamp fixed to the crank shaft of the engine at dead center, interengaging slidable members connected to the lower end of said grinder element and to said clamp to form a support for the lower end 15 of said grinder and permit reciprocation thereof.
13. A cylinder grinder as defined in claim 12, including an auxiliary support for the lower end of said grinder located in the lower end of said cylinder and retractable therefrom by pressure 20 from said grinder.
14. A cylinder grinder as defined in claim 12, in which the interengaging slidable members include a guide cylinder attached to the clamp and a guide rod having a working fit in said cylinder 25 and attached to said grinder.
15. In a cylinder grinder adapted to grind the inner surface of an engine cylinder, a support for said grinder at one end of said cylinder, a guide rod on the end of the grinder opposite said 30 support, a support below said cylinder engaging said rod and permitting reciprocation and rotation thereof, and fingers on said support engaging the inner surface of said cylinder to center the support therein.
16. A grinder as defined in claim 15, including a plurality of springs constantly urging said fingers into engagement with the cylinder, and means limiting the outward movement of the 35 fingers.
17. A cylinder grinder as defined in claim 15, in which said last named support is retractable from the cylinder by action of the grinder.
18. In a cylinder grinder of the character described, a grinder body adapted to rotate and reciprocate within a cylinder to be ground, a plurality of stones extending axially on said body and adapted to expand radially thereto, means 40 to expand the stones at the beginning of the stroke, means including a support above the stones to effect rotation and reciprocation thereof, a support below said stones including a guide cylinder with a guide rod reciprocable therein to prevent drifting of the grinder, and means 45 independent of said upper support to withdraw the lower support at the conclusion of the grinding action.
19. In a cylinder grinder of the character described, a mounting block adapted to rotate and reciprocate within a cylinder to be ground, a plurality of stones mounted axially on said block and adapted to expand radially thereto, a spline shaft attached to said block and coaxial therewith, a gear splined on said spline shaft, means 15 to rotate said block through said gear, reciprocating means mounted above said spline shaft and connected thereto, and a thrust bearing interposed between said spline shaft and said last named means permitting the rotation of the shaft 20 independent of the means.
20. A cylinder grinding machine adapted to grind the cylinder of an engine having a crank shaft, a plurality of stones adapted to move axially in a cylinder and expand radially therein, 25 a support above the stones adapted to permit rotation and reciprocation thereof, and a support below the stones including a member adapted to reciprocate with the stones, and a fixed member attached to the crank shaft at dead center and engaging said other member to form 30 a guide for the lower end of the stones.
21. In a cylinder grinder of the character described comprising, a grinder mounting block adapted to rotate and reciprocate in the cylinder 35 to be ground, a plurality of stones mounted axially on said block and adapted to expand radially thereto, a withdrawable support mounted beneath said block and comprising a guide cylinder fixed on the mounting block coaxially therewith, a guide rod mounted coaxially with said guide cylinder and engaging the same to form a guide for the lower end of said block, and means to withdraw the guide rod from said cylinder after 40 a predetermined number of strokes of the 45 grinder.
